UNITED STATES PATENT OFFICE

166,637

KITE

Floyd M. Robey, Indianapolis, Ind.

Application April 2, 1951, Serial No. 14,683

Term of patent 14 years

(Cl. D34—15)

To all whom it may concern:

Be it known that I, Floyd M. Robey, a citizen of the United States, resident of Indianapolis, Indiana, have invented a new, original, and ornamental Design for a Kite, of which the following is a specification, reference being had to the accompanying drawing, forming a part hereof.

Fig. 1 is a perspective view of the kite in flight, showing the front face of the kite;

Fig. 2 is an end elevation of the kite;

Fig. 3 is a plan view of the rear face of the kite; and

Fig. 4 is a side elevation, the whole showing my new design.

I claim:

The ornamental design for a kite, as shown.
FLOYD M. ROBEY.
